Inventor:

UNITED STATES PATENT OFFICE.

FREDERICK D. VOLLMER, OF MOLINE, ILLINOIS.

SAD-IRON.

1,216,522.

Specification of Letters Patent. Patented Feb. 20, 1917.

Application filed May 1, 1916. Serial No. 94,811.

To all whom it may concern:

Be it known that I, FREDERICK D. VOLLMER, a citizen of the United States, residing at Moline, in the county of Rock Island and 5 State of Illinois, have invented certain new and useful Improvements in Sad-Irons, of which the following is a specification.

The invention relates to improvements in sad irons in which gaseous fuel is ignited 10 within the interior of the body portion of the iron for heating the smoothing surface thereof.

It is an object of the invention to provide a self contained iron of this character having the usual body portion of triangular formation and including a smoothing surface, the body having arranged interiorly thereof suitable heat conducting ribs for conveying the heat generated therein upon 20 the smoothing surface of the iron. It is particularly desirable in irons of this character to concentrate the heat upon the smoothing surface of the iron, and at the same time to retain the upper portion of the iron in a relatively cool state, and to this end I provide a baffle plate overlying the heat conducting ribs, which directs the heat upon the smoothing surface of the iron so that this portion of the iron is at all times 25 relatively hot, while the upper portion or cover of the iron carrying the usual handle remains cool, thereby protecting the hand of the operator, even if the iron is used continuously for substantial periods.

In carrying out my invention I preferably provide a baffle or deflector of concave formation having a peripheral deflecting flange extending therearound, save at its rear end for directing the heat waves upon 30 the bottom of the iron at each side thereof after the heat has traversed the central portion of the iron. The baffle plate is spaced from the cover of the iron a considerable distance to permit air to freely circulate between the cover and baffle, thereby preventing the cover from becoming unduly 35 hot and necessarily protecting the handle.

With these and other objects in view, the invention consists in a novel arrangement 40 and combination of parts to be more fully described and pointed out in the claims.

In the accompanying drawings, Figure 1 illustrates a vertical longitudinal sectional view with parts shown in elevation.

Fig. 2 is a top plan view of the body of 55 the iron;

Fig. 3 is a cross sectional view of Fig. 1;

Fig. 4 is an end view illustrating the burner carrying door; and

Fig. 5 is a top plan view of the deflector. 60

Referring now more particularly to the drawings, wherein like numerals indicate corresponding parts, the numeral 1 designates the interior of the body portion of the iron having the usual upstanding sides 2 65 and smooth surface or bottom 3. The body of the iron is preferably of the usual triangular formation, and the upstanding sides 2 thereof extend from the rear end of the iron to the front portion thereof, the 70 rear wall or side of the body being cut away to provide an opening for the positioning of a movable unitary burner carrying door 4, the particular construction of which will be later described. Disposed within the iron 75 and spaced a slight distance from the sides 2, but extending parallel therewith, are the heat conducting ribs 5, preferably of segmental formation, and of a length less than the length of the body portion of the iron. 80 These ribs project upwardly from the bottom of the iron a substantial distance and are connected near each of their ends with webs 5' of a height somewhat less than the height of the heat conducting ribs 5. These webs 85 5' provide restricted heat conducting passages for the products of combustion generated within the body of the iron, whereby these products are directed upon the bottom of the iron at the proper point, and also afford seating means for a deflector plate to be presently described. The side walls 2 of the iron at their upper edges are cut away intermediate their ends to provide relatively long air passages 6, while the corners of the 90 iron have the usual upstanding portions 6'. A cover plate 7 of triangular formation, and being relatively flat, overlies the body and is fastened to the corner portions 6' thereof by suitable fastening screws 8 passing therethrough, the air passages 6 underlying the cover and permitting the free circulation of air under the plate 7, and serving to retain the cover relatively cool. The usual handle 9 is fastened to the cover 7 by suitable fastening devices, and this handle is of any 95 well known construction.

Positioned below the cover 7 and spaced

therefrom is the deflecting plate 11 of concave formation having the downwardly projecting peripheral flange 13 extending entirely therearound, save at its rear end, and projecting within the body to a point below the upper edges of the heat conducting ribs 5 and spaced laterally therefrom so as to provide passages 12 between the heat conducting ribs 5 and the peripheral flange 13 for the passage of the heat generated within the iron so as to direct this heat upon the smoothing portion of the iron at each side thereof. The heat thus generated is caused to travel through these passages by webs 5', which prevent the escape thereof around the front and rear portions of the deflector plate, it being obvious that it is highly desirable to concentrate the heat upon the smoothing surface of the iron at these points. The deflector plate 11 is secured to the body of the iron by coupling screws 14 passing therethrough and entering sockets within the standards 15, which project inwardly from the segmental heat conducting ribs 5. Two of these standards are shown for the sake of illustration, but any number desired may be used. Referring particularly to Fig. 2 of the drawings, it will be seen that the cover 7 is spaced from the heat deflecting plate 11 to provide an air passage therebetween, the air passing through the opening 6 in the wall of the body of the iron and freely circulating between the cover and the deflector, so that the cover is at all times retained in a relatively cool condition. It will thus be seen that if the cover is retained in a cool condition the handle 9 will also be protected from the heat generated within the iron so that this handle is also cool and the hand of the user is therefore protected and cannot be burned by grasping the handle 9.

Pivottally attached to the rear end of the iron is the swinging closure 4 having cutout portions 15' arranged in its sides and upper edge for the passage of air to the burner, the closure being pivottally attached to the body of the iron by the vertical pin 16 passing through a hinge opening 16' within the closure plate, and the cover 7, and entering a socket 17 within the bottom of the iron. The closure at its upper end near one side is provided with a counter sunk portion or pocket 17' into which the pointed end of a fastening screw 19 passing through the cover 55 enters to retain the closure in a closed position. A cutout portion 20 is arranged within the bottom of the iron underlying the closure, and allows the passage of air to the interior of the iron, it being seen that in the present construction the air passages are provided around the edges of the door or closure which permits an ample supply of air to be admitted to the interior of the iron. A stop or shoulder 21 projects upwardly 65 from the bottom of the iron at one end and

limits the inward movement of the pivoted door 4. Carried by the closure and preferably formed integral therewith is a burner 22, which is slightly inclined and points toward the bottom of the iron, this burner 70 having fitted around its ends a woven screen 23, retained in position by an annular ferrule 24. Exposed exteriorly of the door is a coupling portion 25 having an interiorly threaded socket receiving the usual gas feeding tube 26, by which gas is admitted to the burner when the iron is being used. The door burner and pipe connections are formed as a unit, thereby furnishing a simple and efficient structure. A mixing valve 27 of 75 any well known construction is disposed at the end of the tube 26 to properly proportion the amount of air and gas fed to the interior of the iron.

From the foregoing description it will be 85 seen that when it is desired to light the burner 22, the fastening screw 19 is raised and the door 4 swung open, at which time the burner is lighted and the closure then closed. By having the burner inclined the 90 products of combustion are directed along the surface of the iron and enter the heat conducting space disposed within the body thereof, and after traversing the bottom of the iron within this space the heat waves 95 will travel upwardly engaging the deflector 11, which then again directs the heat product downwardly through the passage 12 between the rib 5 and flange 13 so that the heat is not only concentrated upon the bottom 100 of the iron at the center thereof, but also upon each side of the iron, the cold gases being permitted to escape through an outlet 28. The heat is prevented to a great extent from passing around the front and rear ends 105 of the iron by the webs 5', as these webs upon which the flanges of the deflector plate rest provide passages for directing the heat products in the manner as has been described so that the heat is concentrated upon 110 the bottom of the iron at the points where it is most desirable.

Having thus described my invention what I claim is:

1. A sad iron comprising a body of triangular formation, a door having cutout air feeding openings in its sides and top edge hinged to said body, a burner carried by the door and being disposed in an inclined position for directing the products of combustion upon the bottom of the iron, a movable locking device carried by the iron and engaging said door for locking the same in a closed position, a stop for limiting the inward movement of the door, and air feeding 112 opening in the bottom of the iron underlying the door, and means for feeding fuel to the burner.

2. A sad iron comprising a body portion having a burner located therein, a cover 13

provided with a handle secured to the body, relatively long heat conducting ribs projecting upwardly from the bottom of the iron, webs extending from the sides of the iron 5 to said ribs, a deflecting plate located within the body and having a downwardly extending flange projecting below the upper edge of the heat conducting ribs and resting upon the connecting webs, the said 10 downwardly projecting flange of the connecting plate being spaced laterally from the ribs to provide passages for directing the heat waves upon the bottom of the iron at each side thereof, substantially as described.

3. A sad iron comprising a body portion, having a gas burner located therein, a cover provided with a handle secured to said body, the wall of the body at its upper edge having 20 cutout portions therein providing air passages, relatively long spaced conducting ribs of segmental formation projecting upwardly from the body, webs disposed near each end of said ribs and projecting from 25 the side of the body to said ribs, a deflecting plate positioned within the body and spaced from the cover to provide an air passage therebetween, the said deflector plate having a downwardly extending flange projecting entirely therearound, save at the rear end of the plate, and extending to a point below the upper edge of the heat 30 conducting ribs and resting on the connecting ribs, the said flange of the deflector plate being spaced laterally from the ribs to provide air passages for directing the heat rays upon the bottom of the iron substantially as described.

4. A sad iron comprising a body portion having a fuel burner therein, a cover pro-

vided with a handle secured to the body, heat conducting ribs projecting upwardly from the bottom of the body, a deflecting plate located within the body and having a downwardly extending flange projecting to 45 a point below the upper edge of the heat conducting ribs and laterally spaced therefrom, the said downwardly projecting flange of the deflecting member providing with the heat conducting ribs, passages for 50 directing the products of combustion upon the bottom of the iron.

5. A sad iron comprising a body portion and a burner, a cover for said body, heat conducting means within said body, a deflecting means disposed within the body and having a downwardly extending portion projecting to a point slightly below the upper portion of the heat conducting means and spaced laterally therefrom providing 55 with the heat conducting means passages for directing the products of combustion upon the bottom of the iron at each side thereof.

6. A sad iron comprising a body portion 65 having a burner located therein, heat conducting parts projecting from the bottom of the iron, webs extending from said heat conducting parts, a deflector member located within the body and having a downwardly extending flange projecting below 70 the edge of the heat conducting ribs and resting upon said connecting webs, for the purpose described.

In testimony whereof I affix my signature 75 in the presence of two witnesses.

FREDERICK D. VOLLMER.
